UNITED STATES PATENT OFFICE.

ETHEL G. STAFFORD, OF BRADENTON, FLORIDA.

DENTAL FLOSS HOLDER.

Application filed December 24, 1926, Serial No. 156,921. Renewed July 13, 1928.

This invention pertains to dental floss holders of that type designed for use by individuals.

Objects of the present invention are to provide a dental floss holder of an exceedingly simple construction, one that can be made readily and at low cost, and yet have the advantages of enabling the user to draw the floss taut and secure it by a very simple method.

Another object is to so fashion a dental floss holder that it can be made of spun and stamped metal, celluloid or other desired material and yet be strong and efficient in use.

In addition, the invention is directed to certain details of construction and arrangement of parts to be pointed out herein and form the subject of some of the appended claims.

In the accompanying drawing,

Figure 1 is a longitudinal section of a dental floss holder constructed according to my invention.

Figure 2 is an end elevation of a bobbin together with a shaft, the latter being shown in cross section.

Figure 2^a is a side elevation of a closure portion shown in Figure 1.

Figure 3 is a side elevation of a tubular handle portion.

Figure 4 is a transverse section of the tubular handle on line 4—4 of Figure 3.

Figures 5 and 6 are respectively a transverse section of a body portion shown in Figure 1 and of a cap portion shown in Figures 1 and 2^a.

Figure 7 is a longitudinal section of a modified form of a part of the invention.

Figure 8 is a longitudinal section of a holder similar to that shown in Figure 1 but slightly modified in form.

Figure 9 is a longitudinal section of another modification of the invention, and

Figure 10 is a longitudinal section of a one-piece bobbin and shaft.

The body-portion of the holder is denoted at 1 and may be provided with the usual arms 2 between which to stretch the floss 3, one of the arms preferably having a button 4 thereon about which to wrap the floss whereby it may be positively held.

Said body-portion is provided with a recess 5 to receive one end of a tubular handle-portion 6 best shown in Figure 3.

The opposite end of the said handle-portion receives upon it a slip-cap 7 forming a

closure, said cap having in opposite walls, Figure 6, an inwardly extending tit 8 adapted to enter an angular groove 9 in opposite walls of the handle, Figure 4, said grooves being created by forcing inwardly the material of said handle, it being clear that said cap and handle may be held in connected relation by entering said tits of the cap into the ends of the grooves where they open at the end of the handle, and then turning said cap about the latter, forming a particularly convenient and effective method of connection, the tits and grooves being readily formed in the parts whether of sheet metal or of a non-metallic substance.

The outer surface of the cap 7 is tapered toward its outer end as shown in Figures 1 and 2^a and is adapted to receive upon it a member 10 having an inwardly tapered bore 10', the walls of the member adapted to engage the cap by friction, the purpose of which will appear later. The end of the handle-portion that enters the bore 5 of the body 1 is provided with oppositely disposed grooves 11, but one of which is shown, Figure 3, these corresponding to the grooves 9 already described as to use and purpose. As with the cap 6, the walls of the body 1 for the recess 5 are furnished with inwardly projecting tits 12, Figure 5, to enter the grooves 11 as in the instance first mentioned. By the means thus set forth the whole structure thus far described when assembled is a complete unit.

In the body 1 at the bottom of the recess 5 is a socket 13 disposed centrally of the latter and receiving one end of a shaft 14 whose other end is reduced in diameter leaving a shoulder 14', the reduced portion extending freely through the cap 7 and fixed in any suitable manner in the member 10. Said shaft has a groove 15, Figure 2, extending therealong and 16 is a spool or bobbin slidable along the shaft and having a feather 17 extending into said groove 15.

The extremities of the arms 2 are notched, not shown, in the usual way whereby to retain the floss 3 therein, said floss extending into the handle 6 through a slot 18 in the latter, which slot is partially covered by the body when seated in the recess 5, a small opening being exposed at the bottom of the slot through which the floss may be drawn.

The shoulder 14' of the shaft 14 prevents the latter from leaving the cap 7 and since the member 10 and the shaft are fixed relatively the parts of the structure just consid-

ered are a unit. Said shoulder 14' is spaced slightly from the end wall of the cap 7 so that the latter and the member 10 can have relative movement, or so that the frictional engagement thereof can be made or broken at will. The shaft has control of the bobbin 16 and since the member 10 is affixed to the shaft the separation of the member and cap permits the shaft to be turned to stretch the 10 floss across the arms 2 and said shaft being freed permits the floss to be drawn out upon the arms and attached before being drawn taut.

The bobbin is permitted to move along the 15 shaft in order that as the floss is removed from time to time said bobbin may properly present itself to the place of outlet for said floss.

In Figure 7 is shown a slight modification 20 of the friction means wherein 18 is the tubular handle, and 19 is a member answering in the capacity of the cap 7 of the earlier figures but having an inwardly tapered bore 20 in its outer end to receive the tapered shank 21 of 25 a member 22 corresponding in purpose to the described member 10, a shaft 23 being fixed in said member 22 as in the first example. This structure is, of course, a mere reversal of the earlier form.

Again, Figure 8 which in the main may be 30 constructed as are other forms herein, is modified with respect to the manner of constructing and arranging the outer or free end of the handle represented in this instance by 35 24. It is observed that it has a closed end wall 25 and that said handle at that end is tapered to receive the member 26, corresponding to 10 of the other figures, the inner wall surfaces of said member being formed to frictionally engage the tapered handle-end. The 40 shaft 27 is shouldered at 28 as before and the reduced end passes through the wall 25 and is fixed in the member 26. Whereas in Figure 1 the cap 7 and member 10 are removable 45 from the handle together with the shaft 14, in this instance the handle 24 and member 26 remain in connected relation, the whole being detachable from the body-portion.

In Figure 9 the handle denoted at 28 may 50 be screw threaded at its outer end and the cap 29 may be screwed upon it in lieu of the groove and tit construction previously described. In this form the bobbin 30 may be a part of the shaft 31, Figure 10.

The manner of frictional engagement of 55 the members 10, 22, 26 and 32, it may be seen, is optional through the several forms described as being novel methods, it is believed, in a dental floss holder.

60 I claim—

1. A dental floss holder including in its construction a body-portion having a socket in one end, a tubular handle portion, seated therein adapted for withdrawal, a bobbin in 65 said handle-portion, a rotatable shaft on

which the bobbin is carried, the same extending through and outside the handle, and a member affixed to the shaft outside said handle portion with a conical bore to engage over the handle adapted to be held thereon by frictional engagement. 70

2. A dental floss holder including in its construction a body-portion and a tubular handle terminating in a tapered outer free end, a bobbin in said handle, a shaft rotatable within the handle to carry and positively rotate the bobbin, and a member fixed with respect to the shaft and having a tapered bore complementary to the tapered end of the handle adapted to frictionally engage the 80 same. 75

3. A dental floss holder including in its construction a body-portion and a tubular handle extending therefrom terminating in a conical surface at its free end, a bobbin in said handle, a shaft extending through the handle to carry and positively rotate the bobbin, the same extending from said free end of the handle and having a fixed member thereon having a surface complementary to said conical surface of said handle adapted to engage the same by friction for securing the shaft against rotation. 90 85

4. A dental floss holder including a body portion having a laterally extending arm, a tubular handle-portion extending from the body, a bobbin in said handle for holding floss stretched between it and said arm, said handle having a conical surface at its free end, a shaft engaging and rotating the bobbin terminating outside the handle, and a member affixed to the shaft having a surface complementary to said conical surface of the handle adapted to engage the same by friction. 95 100

5. A dental floss holder including a body-portion having a laterally extending arm, a tubular handle-portion for the body detachable therefrom and having a closed conical end, a member adapted to fit on said conical end and held thereon by friction, a bobbin in said handle, and a shaft carrying the bobbin with which the latter is rotatable, said shaft extending through the closed end of the handle and fixed in said member. 105 110

6. A dental floss holder including a body-portion having a laterally extending arm, a tubular handle-portion engageable with the body-portion, the said handle-portion and said body-portion having complementary means for holding them in connected relation, a bobbin in the tubular handle for receiving windings of floss, a shaft to engage and rotate the bobbin, said shaft extending outside the handle, and a member having an extended conical surface adapted to engage 115 a complementary surface carried by the handle for securing the same by friction for holding the shaft from rotating. 120

7. A dental floss holder including a body-portion having a laterally extending arm 125

and a tubular handle, a bobbin in the handle for receiving windings of floss attached to said arm, a shaft separate from the handle for rotating the bobbin, the same extending outside the handle, and a member affixed to the shaft having an extended conical surface adapted to frictionally engage the handle for securing the shaft from rotation.

8. A dental floss holder including a body-
portion having a laterally extended arm to
which to attach the floss, a tubular handle,
means on the body and handle complementary
to one another for securing the said
body and handle together preventing them
being pulled apart, a bobbin in said handle,
a shaft controlling the bobbin and extending
to the free end of the handle, and a member
fixed with respect to the shaft and having
a conical surface adapted to frictionally en-
gage a complementary surface of the handle
preventing the shaft rotating.

9. A dental floss holder including a body-
portion, a tubular handle attachable thereto,
there being an angular groove in one of the
parts and an extension in the other for en-
gagement holding the two parts in connected
relation, a bobbin in said handle, a shaft en-
gaging the bobbin for positively rotating it,
the same extending to the free end of said
handle, and a member fixed with respect to
the shaft and having a surface to engage by
friction a held part of the handle for securing
the shaft and bobbin from rotation.

10. A dental floss holder including a body
having a recess in one end, the wall of the
recess having a projection extending into said
recess, a tubular handle-portion adapted to
enter the recess and having an angular de-
pression in its outer surface to receive into
it the said projection of the body, a shaft ex-
tending longitudinally through and outside
the handle-portion, there being a socket in
the body at the bottom of the described re-

cess in the latter to receive the inner end of
the shaft, a bobbin on said shaft enclosed in
the handle-portion, a cap attachable to the
outer end of the latter, the said shaft extend-
ing therethrough, and a member fixed with
respect to the shaft adapted to frictionally
engage the said cap.

11. A dental floss holder including in its
construction a handle portion having a pair
of spaced bridging members for a strand of
floss, a floss holding bobbin, and a shaft ro-
tatable within the handle, said bobbin being
mounted on said shaft and at all times free
to shift along said shaft.

12. A dental floss holder including in its
construction a handle portion including two
spaced laterally extending arms across which
to stretch a strand of floss, a floss holding bob-
bin within the handle, a support also within
the handle lying longitudinally thereof, said
bobbin being carried on the support and free
at all times to shift therewith, there being an
opening in the handle opposite the bobbin
through which the floss may be drawn from
said bobbin.

13. A dental floss holder including in its
construction a hollow handle having an open-
ing in its side, a floss holding bobbin in said
handle, a support within and lying longitudi-
nally of the handle for carrying said bobbin
and along which the latter is at all times free
to shift at said opening.

14. A dental floss holder including in its
construction a hollow handle having an open-
ing in its side, a rotatable support within and
lying longitudinally of the handle, and a bobbin
mounted on the support free to shift
therewith opposite the opening but being
otherwise operatively connected to the sup-
port to be rotated thereby.

In testimony whereof I affix my signature.

ETHEL G. STAFFORD.
